MECHANICAL CLEARANCE REGULATOR

Otto M. Burkhardt, Cleveland, Ohio, assignor to
Thompson Products, Inc., Cleveland, Ohio.

Application April 13, 1933, Serial No. 666,038

15 Claims. (Cl. 123—90)

My invention relates to a mechanism for, automatically regulating the clearance within very close limits in the linkage of valve mechanisms, and of eliminating the surge within the linkage system of valve mechanisms for use with internal combustion engines.

The general object of my invention is to provide a regulating device which automatically, efficiently, and with a minimum of parts, adjusts the clearances in the linkage system of valve mechanisms, for every complete cycle of the engine and for all conditions of operation, such as during starting up, speed changes, for all variations in power output, temperature and wear.

Another object of my invention is to provide means that will reduce to a minimum the surge which occurs in all conventional valve mechanisms by reducing and absorbing impacts which are very detrimental to the proper functioning, the endurance, and the safety of the engine at high speeds.

As is well known to those who are familiar with the art of internal combustion engines, their valve operating mechanisms require frequent adjustment to insure a definite clearance between the valve and its actuating member, the conventional cam. This clearance is necessary in conventional mechanisms to allow for expansion of the linkage between this cam and the valve, otherwise the valves would not properly close the combustion chamber, resulting in inefficient combustion.

Because of improper seating of the valve or the entire lack of seating due to lack of clearance in the linkage of the mechanism, the valve is deprived of a most essential cooling period which normally occurs during its contact with the water-cooled seat in the combustion chamber. This aggravates the heating of the valve and causes further expansion and, consequently, worse seating. The valves will then start to warp, burn, crack and break. This is often followed by serious damage to the engine.

If the clearance between the valve and its actuating members increases, either due to normal wear of the cooperating members, or due to a differential in expansion of these members and their supports, then the valve mechanism becomes objectionably noisy and the impact forces are greatly increased, causing pounding of valve seats, excessive wear, surge, and breakage.

Strictly speaking, a warm-up period follows every increase in throttle opening because the heat increases directly with the power output.

Cooling-off periods occur every time the throttle opening is decreased. These differentials in expansion and contraction change the clearance and with it the valve timing. This is detrimental to the proper functioning of the engine.

It is further well known to automotive engineers that within the valve mechanism there exists considerable surge. In general, this surge is noticeable at higher engine speeds but more particularly is it noticeable at certain speeds known as resonance speeds. This surge interferes with the desired true kinematic relation between the valve and its actuating member, the cam.

This surge is the cause of the valve bouncing off its seat when it is expected to close and remain closed. Bouncing of the valve causes very high uncontrolled closing velocities and consequently high impacts. The latter are the cause of pounding away of valve seats, excessive noise, excessive wear, and failures. Bouncing of the valve further causes a delay in closing of the valve which results in loss of power.

Various devices for automatically adjusting clearances in the linkage system of valve mechanisms have been previously developed. The present invention overcomes many difficulties encountered in the construction and operation of such devices. An arrangement operative on a principle similar in some respects to that of the present invention is shown, described and claimed in my Patent Serial No. 1,948,063, February 20, 1934.

Several preferred forms of mechanism by which I accomplish the objects above set forth are illustrated in the accompanying drawings as applied to an L head engine and also an overhead valve type engine. The above stated objects and my device for eliminating the difficulties outlined will become more apparent in the following description which relates to these drawings, in which

Fig. 1 is a fragmentary cross section of an engine block of the L head type, showing an adaptation of my invention to a valve mechanism;

Fig. 2 is a similar fragmentary view showing the position of the parts during a subsequent operation;

Fig. 3 is a fragmentary elevation taken along the lines 3—3 of Fig. 1;

Fig. 4 is a simplified force diagram illustrating the forces present during certain operating conditions;

Fig. 5 is a fragmentary plan view taken along the lines 5—5 of Fig. 1;

Fig. 6 is a fragmentary vertical section similar to Fig. 1, showing a modified adaptation of the 5 regulating cam mechanism;

Fig. 7 is a fragmentary horizontal section taken on a plane indicated by the line 7—7 of Fig. 6;

Fig. 8 is a vertical fragmentary section showing 10 an adaptation of my invention to the rocker arm arrangement of an overhead valve type of engine; and

Fig. 9 is a fragmentary sectional plan taken on 15 an offset plane indicated by the line 9—9 of Fig. 8.

In the arrangement of my invention as illustrated in Figs. 1, 2, and 3, there is shown a valve 10 having the usual stem 12 on which is disposed the usual valve closing spring 14 positioned as shown between a stationary guide collar 16 and a valve spring cap 18 secured by the usual 20 retainer lock indicated at 19.

A valve lifter element 20, which through this invention is greatly simplified by not requiring 25 any adjustment, is slidably positioned in a guide provided in the motor casing 22. This guide is also greatly simplified because the lifter is a plain cylinder not requiring the enlarged head of conventional lifters. The lifter's upper end is in 30 contact with the lower end of the valve stem 12 as indicated at 24. The lower end of this lifter element 20 is shown as resting against the flat side of a spherical element 26 mounted in a co-acting socket 28 in the valve-actuating lever 30.

35 The end 32 of the lever 30 which is nearest the valve center line is bifurcated, and within it is suitably mounted a roller 34 which during the valve opening period is vigorously urged downwardly into contact with the surface of the cam 36 by pressure from the valve spring 14. When the valve is closed, the downward pressure of the valve spring 14 is reacted by the stationary valve seat 15 and its effect on roller 34 ceases.

In the form shown, the end 38 of lever 30 is 40 also bifurcated to carry by means of a pin 42 a regulating spiral or wedge-shaped cam member 40. For the design under consideration two non-rotating but slidable blocks 46 are further mounted on pin 42. These blocks are located to the 45 right and left of the cylindrical end portion designated 38 of the lever 30 and they rest against coacting surfaces 47 provided on the motor casing. The cam 40, having flat sides, also mounted on pin 42, is held in position by a slot provided 50 in end 38 of lever 30. The cam is free to perform a limited angular motion about the axis of pin 42. In order to continuously urge the thick part of the wedge-shaped cam 40 between suitable cooperating surfaces so as to take up excess 55 clearance, a spring 44 is employed. This spring, in the case of Figs. 1, 2, 3, has both ends anchored to the non-rotating but slidable blocks 46. The middle portion of this spring acts on the wedge-shaped cam as shown at 48. The 60 spring preferably consists of a number of turns and is normally under tension urging the thick part of cam 40 between cooperating surfaces. One of these cooperating surfaces is a flexible member 50 which under normal pressure yields 65 a very small amount.

Theoretically, the support 50 need not necessarily be of flexible metal but cam 40 may operate efficiently by engagement with an ordinary support for bearing engagement therewith. Flexibility within the body of metal may be all that 70

is required. However, the flexible support 50 will be found to produce better results and to act more efficiently and is therefore deemed advisable for accomplishment of the best results.

The outer surface of cam 40 is so shaped that a pressure exerted on this outer surface will not pass through the center of the hole in the cam which coincides with the center line of pin 42 but will give rise to a force couple. This force couple is smaller than the sliding friction between the cooperating surfaces, that is, between the contact surfaces of cam 40 and support 50 and between cam 40 and pin 42. This feature makes cam 40 self-locking against the action of this force couple and hence against all static pressure acting on cam 40. If, however, support 50 yields, a relative motion must take place between the contact surfaces. The friction force between cam 40 and support 50 is opposed to sliding of the surfaces relative to each other and therefore it induces cam 40 to roll relative to support 50 an amount corresponding with the amount of deflection of support 50. It will be obvious from the design that the force couple above mentioned as well as the relative motion between the contact surfaces combine to induce cam 40 to roll toward the thin part or clockwise on pin 42. This lowers end 38 of lever 30 and with it to a smaller extent valve 10 relative to cam lobe 37. Because of this the valve opens a few thousandths of an 30 inch less than it would open if end 38 of lever 30 were not lowered. The outer surface of cam 40 may follow the laws of a logarithmic or an arithmetic spiral, or it may follow an involute or some other desirable curve.

To open the valve, only vertical pressure is required. When cam 36 is rotated to urge through its lobe 37 the roller 34 upward, the actuating force will be normal to the surface of cam lobe 37 and will pass through the center of roller 34. The direction of this force varies, hence provision has been made through the proper locating of support 50 and slidable blocks 46 which bear against surfaces of the motor casing, to constrain end 38 of lever 30 from all motion except that required for opening the valve and for regulating the clearance, namely to follow the yield of support 50.

A very simple form of clearance regulating device is obtained by correctly shaping lever arm 30 and by locating the roller 34 at end 32, and the clearance regulating parts at end 38 of lever 30 in efficient relation to cam 36. In the form shown in Figs. 1, 2, and 3, the lever 30 and the various clearance regulating parts mounted on it are so located that the forces between cam lobe 37 and roller 34 during the entire valve opening period act preponderately upward and with a bias to the right so arranged that whatever horizontal component forces there are, they act in the arrangement here chosen preponderately to the right and so hold through the common pivot pin 42 the blocks 46 and with them the entire assembly of lever 30 in the desired position.

To insure further that if any horizontal forces might act to the left they will not force lever 30 and the clearance regulating members out of their desired position, the support 50 is slightly inclined so that any force acting normally upon it through cam 40 will be opposed in a manner that lever 30 can not be displaced to the left. There is another reason for inclining support 50 which will be apparent from the following.

The location for lever 30 and the parts mounted upon it are chosen so that during the valve-open-

ing period a suitable part of the valve spring pressure plus the inertia of the reciprocating parts acts downwardly on end 38 of lever 30. A downward pressure will produce a slight deflection of the support 50 and, consequently, blocks 46 will slide a small amount downward relative to the surface 47. Due to the inclination of the support 50 relative to the surface 47 and due to the frictional adherence of cam 40 to the support 50, and due to a force couple which is the result of the prevailing pressure and the characteristics chosen for the contour of cam 40, this cam 40 will, according to principles previously stated, turn (clockwise in Fig. 1) about the axis of pin 42 an amount which is in direct relation to the small amount of deflection of support 50 and consequently of the downward movement of end 38 of the lever 30. This downward movement is controlled by correctly proportioning the following. First, the magnitude of the downward pressure transferred through lever 30 from the point of application of the main force, the pressure of valve spring 14 plus the inertia of the reciprocating parts to end 38 of lever 30. Second, the yield of the flexible support 50. Third, the contour of cam 40 which rolls a definite amount against support 50 toward a smaller radius or toward the thin part of its wedge-like shape during the slight downward motion.

As stated, when the valve closes, all pressure ceases. Because of the clearance regulating mechanism the valve opened, for example, .001" to .005" less than it would open were it actuated through a conventional mechanism. Therefore, the valve will also close before roller 34 has arrived at the concentric or base circle 35 of cam 36. As the roller approaches the base circle after the closing of the valve, a clearance of several thousandths of an inch will tend to develop within the valve-actuating linkage. While this clearance tends to develop, the potential energy stored in the slightly deflected support 50 is released. Its nature is to return to the no-load position and by so doing it forces the end 38 of the lever 30 upwardly by that amount which it yielded due to the flexibility of the support 50. When this is completed, the end 38 of lever 30 still has to move upward by that small amount which the cam 40 provided, due to its partial rotation about pin 42. It is important to note that when the flexible support 50 returns to its unstressed or no-load position, cam 40 does not return to the angular position which it occupied when the downward movement started. The reason for this is, as pointed out before, that during the downward movement there is the frictional adhesion of the points in contact augmented by the action of a force couple causing clockwise rotation of the cam 40 to its thinner or shorter radius portion. On the return to the no-load position of the flexible support, and of the clearance regulating parts, cam 40 does not change its angular position relative to pin 42 because the frictional resistance between the contacting surfaces which might roll cam 40 back to its original position, is now opposed and overcome by that same force couple which previously helped in slightly rolling cam 40.

On the return motion, a rolling of the cam is further opposed by the static friction between cam 40 and pin 42. Due to these factors, namely the force-couple being on downward yield additive to and on return to no-load position subtractive from the friction between cam 40 and support 50, and because tests reveal it to be so, it is an established fact that on the downward motion

cam 40 does roll, but on the upward motion it does not roll back to its original position. This partial rotation of cam 40 on pin 42 provides a little clearance to insure not only proper valve seating but it provides room for any expansion or other change that might have taken place within the linkage.

Now the thick end of cam 40 is constantly urged between support 50 and pin 42, causing end 38 of lever 30 to move further upwardly until all clearance is out of the linkage, namely, when the valve which is now held firmly to its seat by spring 14, stops lever 30 from moving further upwardly. This completes one adjustment for one complete turn of the cam shaft which constitutes one complete engine cycle.

The arrangement shown in Figs. 1, 2, and 3 has the advantage that the clearance regulating parts at the end 38 of lever 30 can be small in diameter, as the parts are mounted alongside of each other rather than on top of each other. Also, the sliding blocks 46 are free to slide considerable distances up or down without encountering structural limitations. This permits of very large changes in the parts of the valve mechanism to take place and the clearance regulating mechanism will readily compensate for this.

Therefore, not only does the conventional adjustment become entirely superfluous, but due to the fact that the position of the flexible member 50 can be lowered or raised relative to the motor casing 22, a very wide range of manufacturing variations and wear changes can occur before limitations in the clearance regulating range approach inefficiency or ineffectiveness.

The construction shown in Figs. 6 and 7 is so conceived that a plurality of eccentrics 61 are mounted upon a common shaft 62, which extends parallel to the axis of the cam shaft. This shaft is supported at intervals by suitable brackets 22. Upon the outside of each eccentric 61 is mounted one wedge-shaped cam 40 with its return spring 44. Alongside of cam 40 with its return spring 44, there is further mounted upon the outside of eccentric 61 the end 38 of lever 30. These parts 45 embrace and substantially cover the outside of eccentric 61 and they are adapted to oscillate on the eccentric 61. The other end of the lever 30 is arranged exactly as in Figs. 1, 2, and 3. The inner end of the spiral spring 44 is fixed in a suitable slot provided on the periphery of eccentric 61. The outer end of this spiral spring is fixed through a pin on cam 40. This cam, as before, may be considered as a spiral wedge which in the arrangement under consideration is wound up on the circumference of the eccentric. The one end of the spiral spring tends to turn cam 40 so that it is wedged snugly between the flexible stop 50 and the eccentric 61. The other end of the spiral spring supplements this action, in so far as it tends to wedge the eccentric 61 between end 38 of lever 30 and the stationary shaft 62. As before, the spiral cam bears upon a flexible support 50 which is secured as indicated. The flexible support is so formed and fastened as to permit of resilient action when pressure is applied thereto through the medium of end 38 of lever 30, eccentric 61 and cam 40. This pressure originates and bears direct relation to forces necessary to open and close the valve.

In the description of Figs. 1, 2, and 3, it was noted that blocks 46 slide downward relative to surface 47. In the arrangement here under consideration, an analogous downward motion of the clearance regulating parts is brought about

through end 38 of lever 30 being mounted upon eccentric 61 and transmitting pressure to this eccentric 61 and so causing it to partially turn about fixed shaft 62. Due to the eccentric 5 mounting of the clearance regulating parts relative to shaft 62, these parts are lowered when pressure occurs during the valve-opening period by an amount corresponding with the yield of support 50. Thus, it will be seen that in the arrangement as shown, end 38 of lever 30 together with eccentric 61, cam 40, return spring 44, and support 50, perform during and immediately following the valve-opening period and under the influence of the prevailing pressures, the desired 10 clearance regulation exactly as described in detail for the arrangement shown in Figs. 1, 2, and 3.

The mathematical principles of valve clearance regulation can best be given by referring to Fig. 4, which is a skeleton of a desirable form of clearance regulator. The support 50 is shown reversed in Fig. 4, with respect to its point of mounting, for the sake of convenience of illustration.

25 Cam 36 is rotated in clockwise direction. The pressure F_R acting normal on the cam surface passes through the center line of the roller as shown. Opposed to F_R is the pressure F_L which is the sum of the pressure of valve spring 14 plus 30 the inertia of the reciprocating parts. It is apparent that:

$$F_{Ra} = F_{Lc}$$

We shall first discuss application when

$$A \cong C$$

45 F_L is vertical while F_R is inclined. The vertical component of F_R being f'_v acts on lever arm C which is larger than c . Because of this, balance of the system necessitates the existence of an 40 other vertical component at end 38 of lever 30 which we call f''_v . Balance of the system requires that

$$f'_v + f''_v = F_L$$

45 F_R has a horizontal component f'_h which is reacted by an equal and opposite force f''_h at end 38 of lever 30.

f'_h and f''_h form a force couple of moment

$$f'_h \times d$$

50 The system is subjected to one clockwise moment $F_L \times c$ counteracted by 2 counterclockwise moments

$$f'_v C \text{ and } f''_h d$$

55 or

$$F_{Lc} = f'_v C + f''_h d$$

The force f''_v is the vertical component of the force F_s which is the pressure exerted by end 38 of lever 30 upon support 50. The horizontal component of F_s is not necessarily equal to f''_h . The horizontal component of F_s resists f''_v only incidentally. Adequate resistance for f''_v is obtained in the guide surfaces 17. Under pressure F_s support 50 yields. Due to friction, the contact points (0) of the cam and support adhere together. Hence, sum of force couple $F_s \times 1$ plus moment of friction at (0) namely $F_s \times f \times R$ of cam cause rolling of cam about pin 42 toward smaller radius of cam. In the latter expression "f" denotes coefficient of friction. R denotes radius of that part of cam 40 which momentarily is in contact with support 50.

75 When force F_L disappears due to closing of

valve, spring support 50 continues for a moment to exert force F_s because of the inertia of the mass of end 38 of lever 30.

The force F_s will gradually approach zero as support 50 and end 38 of lever 30 are returned to 5 the no-load position.

Upon return to the no-load position, moment of force couple F_s is opposed to cam 40 rolling back into original position. This accounts for a small amount of lash being created every revolution, part of which serves to compensate for expansion in linkage while the remainder is taken out by spring 44 through cam 40.

In Figure 4, the support 50 is located to counteract such forces as result when $a \cong c$. In all cases 15 when $a < c$ the component f''_v must act downward. Inasmuch as f''_v is derived from F_s it is evident that in all cases when $a < c$ support 50 must be so located relative to cam 40 that force 20 F_s acts downwardly.

Effectiveness and simplicity of the device are assured by properly positioning the arm 30 in an angular relation with respect to the axis of the valve stem and by locating the ends 32 and 38 of the lever arm 30 so that under all operating 25 conditions there are components of forces acting to hold the clearance regulating members in the desired position. It is also apparent that by suitably varying the angle at which the guide surfaces 17 or the supporting member 50 are disposed, these components may be varied to suit the different conditions that obtain in different 30 designs of engines. It is not necessary, although here shown, that the center line of the valve intersects that of the cam shaft. The principles 35 apply equally as well when the center line of the valve does not intersect that of the cam shaft but passes either to the right or left of it.

When eccentrics are used as in the cases illustrated in Figs. 6, 7, 8, and 9, the thick part of 40 the eccentric may also be located to the right of the axis of the stationary shafts 62 and 83, respectively.

Figs. 8 and 9 represent an application of the clearance regulator to an overhead valve engine 45 now to be described in detail.

Mounted in suitable brackets is a stationary shaft 82 which through the medium of eccentrics 83 affords support for the rocker levers 84. Each rocker lever is provided with an integrally formed 50 collar or hub 85 embracing the eccentrics 83 about which the rocker arms turn. The center of this hub is so located as to obtain the desired relation between pushrod and valve motion. Upon the circumference of each eccentric bushing is mounted a cam 40^b. The outside surface of this cam bears against a flexible support 55 50^b which is secured to the top of the bracket. Cam 40^b having flat sides is free only to perform a limited angular motion upon the circumference 60 of eccentric 83. In order to continuously urge the thick part of the wedge-shaped or spiral cam 40^b between suitable cooperating surfaces so as to take out excess clearance, is a spring 86 which, like the spring 44 above described, has one end 65 fastened to the eccentric and the other end to the cam 40^b. The outer surface of the cam 40^b is shaped as previously described.

When the cam 36 turns, it exerts pressure on 70 pushrod 88. This pressure together with the resistance of valve 18 and the pressure of spring 14^b constitute the total upward pressure on the eccentric. This tends to turn the eccentric (clockwise in Fig. 8) about the stationary shaft. This turning effort is transmitted through cam 75 75

40^b to support 50^b which will yield until its resistance balances the turning effort.

While support 50^b yields in direction of arrow X, the eccentric through cam 40^b pushes in direction of arrow Y. Due to the frictional adhesion between the contact surfaces of cam 40^b and support 50^b, the cam 40^b will tend to follow support 50^b in direction of arrow X, which causes a turning of cam 40^b on eccentric 83. This turning is further helped by a force couple which is due to the pressure of the moment on the contour of cam 40^b. This motion, as previously stated, is entirely within control through properly proportioning the cooperating parts.

Identically as in the previously described arrangements, when the valve closes, the cause of all pressure ceases. Due to the yield of support 50^b the eccentric 83 has slightly turned about shaft 82, raising the center of the hub of the rocker arm 84 which causes the valve to close a little sooner than it would close were it actuated through a conventional mechanism. As the roller approaches the base circle, a clearance of several thousandths of an inch will tend to develop within the valve linkage. As soon as pressure diminishes, the potential energy stored up in support 50^b is released. Support 50^b will through medium of cam 40^b cause eccentric 83 to turn counterclockwise and so urge the hub portion of the rocker arm downward. This eliminates only part of the lost motion brought about during the opening of the valve because during the return to the no-load position of support 50^b, cam 40^b will not turn on eccentric 83 because through the friction between the contacting surfaces of cam 40^b and support 50^b, the potential energy of this support would now tend to cause cam 40^b to rotate clockwise, which it can not readily do because this would involve entering the thick part of the wedge-shaped cam between the cooperating surfaces; but moreover the moment of a force couple due to the design of cam 40^b, counteracts clockwise motion of cam 40^b and eccentric 83. It is only after the effect of the potential energy from support 50^b has been expended that slackness within the linkage tends to develop. This slackness serves first to compensate for whatever expansion may have taken place within the linkage. Only after this is compensated for can all pressure cease. Then spring 86 urges cam 40^b between eccentric 83 and support 50^b and so removes all excess clearance. This constitutes one complete cycle.

While I have described in detail some specific designs and their operation with respect to given types of internal combustion engines, it is to be understood that I may make any number of suitable designs which are within the spirit and scope of the appended claims, and I therefore do not wish to be limited to the particular designs illustrated.

In the early part of this application it was stated that the invention will eliminate surge from the linkage of the valve mechanism. How this is accomplished will appear from the following.

It is well known that the entire valve-opening period which lasts about one-third ($\frac{1}{3}$) of a cam shaft revolution or about 120° cam shaft angular motion, usually less than 30° only are available to accelerate the entire reciprocating valve linkage. Because of the short time available the pressures have to be very high. To avoid other problems the linkage has to be made light. High pressures and light linkage cause appreciable

elastic yield within the linkage. The product of the pressure multiplied by this yield represents the energy which is stored up in the valve linkage. At a car speed of 60 to 70 miles per hour, this storing of energy in the valve linkage occurs in less than .003 second. This time interval happens to coincide with the frequency of conventional valve springs. Coincidences of this nature are recognized as prolific sources of resonance or surge in mechanisms.

More specifically, what happens within the valve linkage is that when the geometry of the cam contour requires a valve velocity of say 50 inches per second, the valve moves at a lesser velocity, perhaps 40 inches per second, more or less. At the beginning of the valve opening period, the valve always lags behind the cam's angular velocity by an amount corresponding to the energy stored up within the valve mechanism due to elastic deformation. Hence resonance or surge is bound to occur within the valve mechanism. The surge frequency of the valve linkage set up by this elastic deformation, remains constant but the angular velocity of the cam is subject to wide variations, due to variations in engine speed and periods in the mechanism which is driving the cam shaft.

These facts briefly account for noticeable surge in the valve linkage. If there is clearance in the valve linkage, the pressure above referred to usually occurs as a shock to the linkage which in turn is known to aggravate this surge. Now inasmuch as the invention eliminates all excess clearance, it is obvious that shocks are reduced and consequently one cause of surge aggravation is eliminated.

It is well known that surge or vibrations in structural parts can be lessened by the use of friction devices which tend to dampen them out. One of the advantageous characteristics of my invention is that it is made up of a number of parts which in the performance of their functions move relatively to one another and so introduce a small amount of friction into the linkage members. This small amount of friction helps further to minimize surge in the entire linkage. Therefore, with the invention I attain not only clearance regulation but surge dampening as well for each cycle of the engine. It is practically impossible for this regulating mechanism to remain in a static non-adjusting, non-dampening condition through a period of a plurality of cycles or valve actuation.

What I claim is:

1. In an internal combustion engine, the combination with a valve and a cam shaft, of valve-operating linkage including a lever interposed between said valve and cam shaft and adapted to transmit motion therebetween, oscillatable cam means associated with one end of said lever, a spring normally forcing the cam in one direction, means permitting movement of the axis of said cam means, and a substantially stationary abutment contacting said cam means, so that said cam means affords a movable fulcrum for one end of said lever and acts to move said fulcrum to regulate clearances and absorb impacts between said valve and cam shaft.

2. In an internal combustion engine, the combination with a valve and a cam shaft, of valve-operating linkage including a lever interposed between said valve and cam shaft and adapted to transmit motion therebetween, oscillatable cam means associated with one end of said lever, a spring normally forcing the cam in one direction,

tion, and means permitting movement of the axis of said cam means so that said cam means affords a moveable fulcrum for one end of said lever and acts to absorb impacts and to regulate clearance between said valve and cam shaft.

3. In a valve mechanism for an internal combustion engine, the combination of a valve, a cam shaft, a lever interposed between said valve and cam shaft, one end of said lever contacting said cam shaft and the other end of said lever having associated therewith an oscillatable wedge-acting cam member, and means permitting movement of the axis of said cam member, said lever being disposed angularly with respect to the movement of said valve and said cam having means normally forcing the same in one direction whereby a preponderant force is at all times exerted in one direction to maintain said lever in an operating position and said cam affords a moveable fulcrum to regulate clearness in the valve mechanism and to insure constrained movement of said lever effecting opening and closing of the valve.

4. In a valve mechanism for an internal combustion engine, the combination with a valve and a cam shaft, of valve-operating linkage including a lever angularly interposed between the said cam shaft and valve, a fixed auxiliary shaft, an eccentric oscillatably disposed on said shaft, said lever embracing said eccentric, a wedging cam oscillatably disposed on said eccentric, means normally urging said cam in one direction, and a reaction element contacting said cam, whereby the force moments about the center of said auxiliary shaft would be unbalanced if substantial clearances should exist in the valve mechanism and whereby said cam and eccentric are automatically actuated by such tendency so as to regulate said clearances.

5. In an internal combustion engine, the combination with a valve and a cam shaft, of a lever interposed between and linking said valve and cam shaft and adapted to transmit motion therebetween, said lever being actuated at its one end by said cam shaft and said valve being actuated from a point on said lever intermediate its ends, and automatically adjustable cam means associated with the other end of said lever and adapted under pressure through said lever to alter the relative inclination thereof to change the linkage distances between said valve and cam shaft, and adapted when pressure ceases to again change the distances to insure minimum clearance.

6. In an internal combustion engine, the combination with a valve and a cam shaft, of an inclined lever interposed between and linking said valve and cam shaft and adapted to transmit motion therebetween, said lever being actuated at its one end by said cam shaft and said valve being actuated from another point on said lever, and automatically adjustable cam means associated with the other end of said lever and adapted under pressure through said lever to alter the relative inclination thereof to change the linkage distances between said valve and cam shaft, and adapted when pressure ceases to again change the distances to insure minimum clearance.

7. In an internal combustion engine, the combination of valve-operating linkage including a lever arranged between the cam shaft and valve stem and adapted to transmit motion therebetween, a wedge-acting cam oscillatably mounted upon the one end of said lever means permitting movement of the axis of said cam, spring means arranged between said cam and lever so as to

normally force said cam towards its larger radius, and a resilient abutment for bearing engagement by said cam, said parts being so constructed and arranged that said cam will be turned about its axis towards its smaller radius during the valve-opening period and being adapted thereby to store energy during said period, and said cam turning automatically towards its larger radius during the post valve-operating period so as to thereby regulate the clearance in the mechanism and to release such stored energy during said post valve-operating period but only to the extent required.

8. In an internal combustion engine, the combination of valve-operating linkage including a lever arranged between the cam shaft and valve stem and adapted to transmit motion therebetween, a wedge-acting cam oscillatably mounted upon the one end of said lever, spring means arranged between said cam and lever so as to normally force said cam towards its larger radius, an abutment for bearing engagement by said cam, a slideable mounting for the end of said lever upon which the cam is mounted and being so arranged as to permit movement of said lever end substantially transversely thereof and towards and from said abutment, whereby said cam will turn about its axis towards its smaller radius during the valve-opening period and being adapted thereby to store energy during said period and said cam turning automatically towards its larger radius during the post valve-operating period so as to thereby regulate the clearance in the mechanism.

9. In an internal combustion engine, the combination of valve-operating linkage including a lever arranged between the cam shaft and valve stem and adapted to transmit motion therebetween, a wedge-acting cam oscillatably mounted upon the one end of said lever, spring means arranged between said cam and lever so as to normally force said cam towards its larger radius, a slideable mounting for the end of said lever upon which said cam is mounted, said mounting comprising a block having slideable engagement with a stationary abutment, a resilient abutment extending angularly with respect to said stationary abutment so as to afford a wedging engagement, the lever end upon which said cam is mounted sliding movement substantially transversely thereof and towards and from said resilient abutment, said parts being so constructed and arranged that said cam will be turned about its axis towards its smaller radius during the valve-opening period and being adapted thereby to store energy during said period, and said cam turning automatically towards its larger radius during the post valve-operating period so as to thereby regulate the clearance in the mechanism.

10. In a valve mechanism for an internal combustion engine, the combination with a valve and a cam shaft, of a motion-transmitting lever interposed between said cam shaft and valve, a fixed auxiliary shaft, an eccentric oscillatably mounted upon said auxiliary shaft, the one end portion of said lever embracing said eccentric, a wedge-acting cam oscillatably disposed on said eccentric, spring means arranged between said eccentric and cam so as to normally urge the two in opposite angular directions, and a substantially stationary abutment for said cam, said parts being so constructed and arranged that said cam will be turned about its axis towards its smaller radius by movement of said eccentric by said lever during the valve-opening period, and

said cam will automatically turn towards its larger radius during the post valve-operating period in response to lack of adjustment in the mechanism.

- 5 11. In an internal combustion engine, the combination with a valve and a cam shaft, of an inclined lever interposed between and linking said valve and cam shaft and adapted to transmit motion therebetween, one end portion of said lever having operative engagement with said cam shaft for actuation of said lever, said valve being actuated from a point between the ends of said lever, a wedge-acting cam oscillatably mounted upon the other end of said lever, spring means 10 arranged between said cam and lever for normally forcing the cam towards its larger radius, means permitting movement of the axis of said cam and an abutment for said cam, said parts being so constructed and arranged that said cam will be 15 turned towards its smaller radius during the valve-opening period and will turn automatically towards its larger radius during the post valve-operating period so as to regulate the clearance in the mechanism.
- 20 12. In an internal combustion engine, the combination with a valve and a cam shaft, of an inclined lever interposed between and linking said valve and cam shaft and adapted to transmit motion therebetween, one end portion of said lever having operative engagement with said cam shaft for actuation of said lever, said valve being actuated from a point between the ends of said lever, a wedge-acting cam oscillatably mounted upon the other end of said lever, spring means 25 arranged between said cam and lever for normally forcing the cam towards its large radius, means affording slidable movement of the end of the lever upon which the cam is mounted and in a direction substantially transversely of said lever, 30 said cam having an abutment extending angularly to the direction of such slidable movement so as to afford a wedging engagement, said parts being so constructed and arranged that said cam will be turned towards its smaller radius during 35 the valve-opening period and will turn automatically towards its larger radius during the post valve-operating period so as to regulate the clearance in the mechanism.
- 40 45 13. In an internal combustion engine, the com-

bination with a valve and a cam shaft, of an inclined lever interposed between and linking said valve and cam shaft and adapted to transmit motion therebetween, one end portion of said lever having operative engagement with said cam shaft for actuation of said lever, said valve being actuated from a point between the ends of said lever, an eccentric oscillatably mounted upon a fixed shaft, the other end of said lever being oscillatably disposed about said eccentric, a wedge-acting cam oscillatably mounted upon said eccentric, spring means for normally forcing said cam towards its larger radius, and a substantially stationary abutment for said cam, said parts being so constructed and arranged that said cam will be turned towards its smaller radius during the valve-opening period and will turn automatically towards its larger radius during the post valve-operating period so as to regulate the clearance in the mechanism.

20 14. In an internal combustion engine, the combination with a valve and a cam shaft, of an inclined lever interposed between and linking said valve and cam shaft and adapted to transmit motion therebetween, one end portion of said lever having operative engagement with said cam shaft for actuation of said lever, said valve being actuated from a point between the ends of said lever, an eccentric oscillatably mounted upon a fixed shaft, the other end of said lever being oscillatably disposed about said eccentric, and cam means 25 having oscillatable connection with said eccentric for controlling the oscillatable movement of said eccentric so as to thereby regulate the clearance in the mechanism.

30 35 15. In an internal combustion engine, the combination with a valve and a cam shaft, of valve-operating linkage including a lever interposed between said valve and cam shaft and adapted to transmit motion therebetween, oscillatable cam means associated with one end of said lever, a spring normally forcing the cam in one direction, means permitting movement of the axis of said cam means, and an abutment contacting said cam means, so that said cam means affords a movable 40 fulcrum for one end of said lever and acts to move said fulcrum to regulate clearances and absorb impacts between said valve and cam shaft.
